C. P. DUBBS

PROCESS FOR TREATING PETROLEUM

Filed June 21, 1919

UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR TREATING PETROLEUM.

Application filed June 21, 1919. Serial No. 305,793.

To all whom it may concern:

Be it known that I, CARBON P. DUBBS, a citizen of the United States, residing in Wilmette, county of Cook, and State of Illinois, have invented certain new and useful Improvements in Processes for Treating Petroleum, of which the following is a specification.

This invention relates to a process for 10 treating petroleum and other hydrocarbons to produce products therefrom, having lower boiling points.

The invention contemplates a process for continuously treating petroleum; a process 15 whereby petroleum is passed through a heating zone, thence through a vaporizing or converting chamber wherein vaporous products are released and the heavier residual material is drawn off; a process in which 20 the vapors liberated in the vaporizing zone are passed through a series of pools of liquid oil subjecting the vapors to a dephlegmating action; a process in which the circulation of the vapors may be controlled by a pump interposed in the vapor line; a process which 25 utilizes the raw oil as a reflux condensing agent, the condensate combining with the raw oil prior to its being introduced to the heating zone; a process whereby an increased 30 amount of the heat generated is utilized in the system; a process in which the raw oil is caused to circulate down through successive pools maintained in the dephlegmator, subjecting the vapors bubbling therethrough 35 to a refluxing action, the raw oil and condensate being drawn off from the bottom of the dephlegmator; a process whereby the oil under treatment is heated in one stage and such heat treatment so controlled and regulated as to prevent any substantial deposition 40 of carbon in such zone; a process in which the oil to be treated is fed continuously or intermittently by passing it through succeeding pools of oil before being passed to the cracking tubes, such oil being freed of that portion having the desired low boiling points while dephlegmating the vapors in said pools.

The invention and apparatus reside in 45 such features of construction and such proc-

ess and method features as will more fully be hereinafter described.

In the drawings:

Fig. 1 is a diagrammatic side elevation in section of an apparatus, by which my process can be carried out. 55

Fig. 2 is a top plan view of the vaporizing chambers and the immediate piping.

Fig. 3 is a top cross sectional view of that section of Fig. 1, in which the pools of oil 60 are shown. This is a cross section taken on the line 3—3 of Fig. 1.

In describing the attached drawing, and operation of the process, the oil to be treated is drawn from a source (not shown), and is 65 forced into the apparatus through valve marked K¹, through line K, through the line K², which section is perforated that extends across the bottom of the top pool of oil in the chamber marked L^x. The portion vaporizing as said oil percolates up through this pool of oil is passed off through vapor line L, through the pressure regulating valve L¹, through gooseneck L², through condensing coil L⁴ positioned in condensing tank L⁷, 70 through line L⁴ into tank M, along with the incondensable gases. Water is fed to tank L⁷ through line L⁵ and travels out of said tank through line L⁶. The condensate collected in tank M is drawn off through line 75 M¹ having positioned thereon pressure regulating valve M², while the incondensable gas is drawn off through line M³ through pressure regulating valve M⁴ and on this tank is a liquid level gauge M⁶ and a pressure gauge M⁷. Tanks M and L⁷ rest on the supports marked X. 80

The level of the top pool of oil in the chamber L^x is maintained at approximately J and any surplus flows through pipe J¹ into 85 the pool of oil directly thereunder, the level of this pool being maintained at point marked J. Any excess travels through line J³ into the bottom of the pool of oil immediately thereunder, the level of this pool being maintained at point J and any excess travelling through the line J² into the pool of oil immediately thereunder and this pool is maintained at a level marked J and any excess travels through line J⁴, having posi- 90

tioned on its valve J^6 . At the bottom of line J^4 , the cross sectional area is reduced as shown at J^6 , the larger sized pipe used in J^4 being for the purpose of allowing the oil to be, more or less, freed of any vapors contained therein, such vapors passing back up through said pipe into the bottom of the chamber L^x . The remaining liquid passes through line J^6 into header A , and passes 10 through lines B into header A^1 . In each of these headers opposite each end of the tubes B are positioned plugs A^3 , for the purpose of allowing entry to said tubes for cleaning same and opposite these plugs are furnace 15 doors A^4 and A^5 , which by opening give ready access to said plugs.

The tubes B and headers A and A^1 are positioned in the furnace A^6 . As the oil passes through these tubes B from header 20 A to header A^1 , it is subjected to heat, which converts a portion into lower boiling point products, and the oil flows from header A^1 through line C , into header C^1 , having positioned therein pyrometer N and 25 through valve C^2 into retort D , which retort has manholes marked D — D , pressure gauge P and pyrometer N .

As the oil passes through tank D , a proportion of same is vaporized and passes up 30 through vapor lines E into header E^1 , through valve E^2 into line E^4 , which also has a pyrometer marked N . Through the line E^4 , the valve E^5 being opened while the valves E^7 and E^{10} are closed, the vapors 35 pass into the bottom compartment of the chamber L^x . Any proportion condensing drains into the bottom compartment of chamber L^x , and is automatically returned to the heating tubes B through line J^4 . The 40 uncondensed portions pass up through the pipes marked F^1 and by means of caps G are forced down and discharged near the bottom into the pool of oil in that chamber. The bottoms of the caps marked G are 45 perforated at the points marked H . The vapors as they bubble up this pool of oil give up more or less of their heat and more or less of same are condensed and as they bubble up through this liquid, they are 50 more or less scrubbed. The excess oil accumulated in this pool travels through pipe J^2 into the pool of oil contained in the compartment directly thereunder, the pipe J^2 extending down into the pool of oil to 55 a point near the bottom, thus forming a liquid seal so that no vapors contained in the lower chamber can pass up through pipe J^2 into the upper chamber. The remaining vapors pass up through pipes F^2 and are 60 forced by means of caps G^1 down to near the bottom of the pool of oil contained in this chamber and there escape into said pool of oil through the perforations at a point marked H in said caps or if these are not 65 of sufficient capacity, the excess vapors can

pass clear down under the bottom of the caps and escape up through the oil from that point.

As such vapors percolate up through this pool of oil, more or less of the heat in same 70 is extracted and acquired by the pool of oil, thus causing more or less of the vapors to condense and be retained in such pool of oil and act to have a scrubbing effect on

remaining vapors. The surplus oil accumulating in this chamber travels through pipe 75 J^3 into the pool contained in the chamber immediately thereunder, such pipe extending to near the bottom of said latter pool, so as to prevent any vapors passing there- 80 through from the latter chamber up into the former chamber. The remaining vapors in the last mentioned pool pass up through pipes F and by means of caps G^2 are forced

down to near the bottom of the pool of oil 85 contained in this chamber and are there discharged into said pool of oil through the perforated places marked H or by passing completely under the bottom of caps G^2 and as they percolate up through this pool of oil, more or less heat is extracted

therefrom and retained in the oil forming 90 this pool, which causes more or less of such vapors to be condensed and retained in this pool of oil and the surplus of such oil over- 95 flows through pipe J^1 into the pool immediately thereunder, being discharged in said pool near the bottom so as to prevent any vapors in said lower chamber passing

through this pipe into the upper chamber. There may be as many pools of oil as are 100 shown in the chamber L^x or as desired or found necessary to sufficiently scrub the vapors passed therethrough and to reduce and condense any desired portions of the vapors

to produce the desired boiling point, the remaining vapors passing from said chamber L^x through pressure regulating valve L^1 , through gooseneck L^2 as already described.

These pools of oil may be contained in one chamber as shown in the drawing and marked L^x or in more than one chamber. The excess oil in the bottom pool of each chamber being returned to the heating pipes

B in the same manner as shown in the drawing, and as this will be readily understood by those versed in the art, I have not deemed it necessary to show more than one chamber

marked L^x .

In case it is desired to stimulate the 110 flow of vapors from the vaporizing chamber into and through the chamber L^x , a pump is provided marked E^8 and connected to the vapor line E^4 by means of line E^6 ,

having positioned on it valve E^7 and on the discharge side of the pump it is connected to vapor line E^4 by line E^9 , having

positioned on it valve E^{10} and to use this pump for pumping, the valve E^5 would be

closed on line E^4 and valves E^7 and E^{10}

115

120

125

130

would be open, and pump put in operation, thereby causing the vapors to travel from line E⁴ through line E⁶, through pump E⁸, through E⁹, back through line E⁴ on the opposite side of the valve E⁵ from which the vapors were originally drawn from line E⁴.

In different parts of this vaporizing chamber are shown pyrometers marked N and pressure gauges marked P. The chamber L^x and pump E⁸ are positioned on supports marked X. The portion of oil in the vaporizing chamber D remaining unvaporized is drawn off either continuously or intermittently through line D³, through valve D⁵ and with it is carried off more or less of the carbon formed in the cracking of the oil. Vaporizing chamber D is duplicated as shown in vaporizing chamber marked D¹. This is for the reason that when it becomes necessary to clean vapor chamber D, the rest of the apparatus can be kept in operation by diverting the flow of heated oil coming from the heating tubes B into the other vaporizing chamber D¹ by the opening of valve C³ and the vapors passed therefrom by the opening of valve E³, and the unvaporized portion in tank D¹ being drawn off through valve D⁵ through line D⁴ and the discharge of the heated oil into tank D being stopped by the closing of valves C² and E². In due time, the manholes marked D—D on this latter tank can be opened and the tank cleaned; said tank will be ready to be put back in service by the time it becomes necessary to clean tank D¹, this being done by the closing of valves C³, and E³ and the opening of valves C² and E². These vapor chambers are supported by supports marked X. Said vaporizing chambers and vapor line marked E and section of vapor line marked E¹ are heavily insulated as indicated by D³¹. The purpose of such insulation is for preventing loss of heat from this section and to prevent any portion of the oil, after once being vaporized, from condensing and mixed back with that portion remaining in the vapor chamber unvaporized. These vapor chambers are maintained only partly full of oil.

It will be noted that the raw oil is fed into the top or last pool of oil, which is of the lowest temperature and flows from there into the next succeeding pool of oil, which is higher in temperature and then to the next, which is still higher, etc. thus being progressively subjected to increasing temperatures and also mixed with such oils as are condensed in these pools of oil and such mixture returned for further heating. Thus, the raw oil being fed in is being preheated before passing to the heating coils B and thus utilizing more or less of the heat given up by the vapors that are passed through these pools of oil. It will

be noted that by this novel arrangement, such portions of the oil, either of the raw oil fed in or that formed by condensing of portions of the vapors as they pass through the different pools of oil that are changed to the desired low boiling point products, pass through the water condenser, and are condensed and collected separately, thus avoiding the necessity of subjecting them to the heat of the furnace A⁶.

Among other advantages of this process is controlling the amount of cracking done on each circuit of the oil through the heating or cracking tubes B, the separation and withdrawal from the apparatus of the unvaporized portion remaining in the vapor chamber along with more or less of the carbon formed, the fractional condensing of the vapors generated and those of not sufficient low boiling point returned to the heating tubes for further heating and cracking, thus being entirely freed from any carbon content before being passed again through said heating tubes and in each circuit of the oil and vapors through the apparatus, that portion that is again passed through the heating coils is always free of all carbon before being subjected to further heating cracking action.

It will also be observed that in this arrangement, great economy in fuel will be gained. The temperature to which the oil is heated may vary from a minimum of 200 degs. F. to 600 degs. F., and from a maximum of 600 degs. F. to 1500 degs F. While the pressure maintained may vary from minimum of a few pounds to the square inch to a maximum of 800 pounds to the square inch. These ranges of temperature and pressure are by no means arbitrary.

While I have shown and described a particular apparatus for carrying out my method, the latter is not limited to the use with the particular apparatus shown and described. Also various changes in the details of construction, connections and operation of the apparatus may be made within the scope of my invention.

I claim as my invention:

1. A process of oil conversion which consists in passing hydrocarbon oil but once through a continuous elongated passageway where the oil is subjected to a cracking temperature, in introducing the highly heated oil to an enlarged chamber with which said passageway communicates, in discharging the vapors from said chamber to a dephlegmator, in introducing charging stock to the dephlegmator to intimately commingle with said vapors to condense the heavier vapors and heat the stock, in discharging uncondensed vapors, in returning to the inlet side of said elongated passageway intermingled condensate and charging stock for passage therethrough, in withdrawing carbon con-

taining residue from said enlarged chamber without permitting any portion thereof to again enter the elongated cracking passageway, and in maintaining a superatmospheric pressure on said system.

2. A continuous process of oil conversion, consisting in passing oil in a stream once through an elongated passageway where said oil is subjected to a cracking temperature, in passing the highly heated oil to an enlarged expansion chamber where a substantial portion thereof vaporizes, in discharging vapors directly from said chamber to a dephlegmator, in substantially continuously introducing charging stock to said dephlegmator to intimately commingle with the vapors passing therethrough to condense the heavy oil vapors in discharging uncondensed vapors from said dephlegmator, in continuously returning condensate with intermingled heated charging stock to the inlet side of the elongated cracking passageway for passage therethrough for treatment, and in maintaining a superatmospheric pressure in said system.

3. A continuous process of oil conversion, consisting in passing oil in a stream through a continuous elongated passageway where said oil is subjected to a cracking temperature, in then passing the said highly heated oil to an enlarged expansion chamber where a substantial portion thereof vaporizes, in discharging the vapors from said chamber to a dephlegmator, in substantially continuously introducing charging stock to said dephlegmator to intimately commingle with the vapors passing therethrough to condense the heavy oil vapors, in continuously returning intermingled condensate and charging stock to the inlet side of the elongated cracking passageway for passage therethrough for treatment, in separately discharging residue from said expansion chamber without permitting said residue to enter the elongated cracking passageway, and in maintaining said system under a superatmospheric pressure.

4. A process of oil conversion, comprising passing hydrocarbon oil once only through a continuous elongated passageway where said oil is subjected to a cracking temperature, in then delivering the highly heated oil to an enlarged chamber, in then passing vapors from said chamber to a dephlegmator, in introducing liquid oil to said dephlegmator to condense the heavier vapors, in passing said condensate and heated liquid oil substantially continuously and without previous mixture with the hydrocarbon products in said enlarged chamber to the inlet side of said elongated passageway for treatment therein, in discharging uncondensed vapors from the dephlegmator for final condensation, and in maintaining a superatmospheric pressure on the oil in said

passageway, enlarged chamber, and dephlegmator.

5. A process of oil conversion, comprising passing a stream of hydrocarbon oil through an elongated passageway where said oil is subjected to a cracking temperature, in delivering the highly heated oil to an enlarged vapor chamber where vaporization thereof occurs, in then passing vapors from said chamber to a dephlegmator, in introducing charging stock to said dephlegmator to condense the heavier vapors, in passing said condensate and heated charging stock continuously and without previous admission to the vapor chamber to the inlet side of said elongated passageway for treatment therein, in discharging uncondensed vapors from the dephlegmator for final condensation, in separately withdrawing residue from said vapor chamber without permitting said residue to enter said elongated passageway, and in maintaining a superatmospheric pressure on the oil undergoing distillation and while in the dephlegmator.

6. A process of oil conversion, consisting in passing hydrocarbon oil in a stream through an elongated continuous passageway where said oil is subjected to a cracking temperature, in passing the highly heated oil to an enlarged chamber, in discharging vapors from said chamber into a dephlegmator, in introducing charging stock to said dephlegmator, in causing the vapors to percolate through oil pools in said dephlegmator where the heavier vapors are condensed, in continuously admitting to the inlet side of said elongated cracking passageway the intermingled reflux condensate and charging stock for passage through the elongated passageway, in removing heavy carbon containing residue from said vapor chamber without returning said residue to said elongated continuous passageway, and in maintaining a superatmospheric pressure in the system.

7. A process of oil conversion comprising passing hydrocarbon oil in a stream once only through a continuous elongated passageway disposed within a furnace where said oil is subjected to a cracking temperature, in transferring the highly heated oil to an enlarged chamber where vaporization of a substantial portion thereof occurs, in discharging vapors from said chamber to a dephlegmator, and in aiding in the condensation of the insufficiently cracked vapors passing through said dephlegmator by introducing to the dephlegmator incoming charging stock, in passing the condensate from said dephlegmator and the charging stock to the inlet side of said elongated passageway to travel therethrough in a continuously advancing stream to be heated to a cracking temperature, in discharging uncondensed vapors from the dephlegmator for final condensation, and in maintaining a

superatmospheric vapor pressure on the oil in said passageway, enlarged chamber and dephlegmator.

8. A continuous process of oil conversion, 5 consisting in maintaining a treated body of oil heated at a cracking temperature in an enlarged expansion chamber where vaporization of said oil occurs, in discharging said vapors to a dephlegmator for passage there- 10 through, in condensing the heavy insufficiently cracked vapors in said dephlegmator by introducing charging stock thereto, in discharging uncondensed vapors from said dephlegmator, and in then heating said 15 charging stock and condensate from said de-

phlegmator to a cracking temperature for introduction to said expansion chamber by continuously admitting the same to the inlet side of continuous elongated conveying means disposed within a heating furnace to 20 flow therethrough once only and to be discharged after said single passage into said expansion chamber, in discharging residue from the expansion chamber without admitting the same to said elongated conveying 25 means, and in maintaining a superatmospheric pressure on the oil undergoing distillation and while passing through said dephlegmator.

CARBON P. DUBBS.
